UNITED STATES PATENT OFFICE.

FERNANDO C. BONIFACIO, OF SAN FRANCISCO, CALIFORNIA.

KEYHOLE GUARD.

Application filed August 16, 1924. Serial No. 732,481.

This invention relates to improvements in locks and more particularly for guards to be mounted upon door locks and the like.

An important object of the invention is to provide a keyhole guard which may be securely positioned against the keyhole of a door lock or the like and prevent opening of the same.

A further object of the invention is the provision of a device of this character which may be positioned on either side of the door lock and prove equally effective in either position.

A still further object of the invention is the provision of a movable keyhole guard of this character which may be easily locked in position and also readily removed.

Other objects and advantages of this invention will be apparent during the course 20 of the following description.

In the accompanying drawings forming a part of this specification and in which like numerals are employed to designate like parts throughout the same:

25 Figure 1 is a front elevation of my improved device,

Figure 2 is a side elevation showing the device mounted in position on a door lock,

30 Figure 3 is a rear elevation of the device,

Figure 4 is a front elevation, parts being broken away to show the interior construction thereof,

Figure 5 is a vertical sectional view taken on the line 5—5 of Figure 4,

35 Figure 6 is an enlarged detail view of the locking device, and

Figure 7 is a horizontal sectional view taken on the line 7—7 of Figure 4.

In the drawings, wherein for the purpose 40 of illustration is shown the preferred embodiment of my invention, the numeral 10 generally indicates the body or casing of my improved guard, this body comprising an end plate 11 and side walls 12. The body 45 is substantially rectangular in shape and is provided in one extremity thereof with a partition plate 13, this plate forming a comparatively narrow compartment 14 at one extremity of the body.

50 Rigidly secured to the inner side of the end plate 11 and positioned approximately in the center thereof is a key pin 15, this pin being somewhat longer than the width of the casing, causing the same to project substantially therethrough. This pin is adapted to receive a suitable key thereon

and guide same during its rotary movement, thereby causing the key to be suitably positioned for unlocking the mechanism. A similar projecting pin member 16 is secured 60 to the outer side of the end plate 11, this pin being preferably positioned near the upper central portion thereof and adapted to engage the keyhole of the door lock. This pin should be of sufficient length to penetrate 65 the greater portion of the keyhole thereby preventing the insertion of a key therein. An extension lug 17 is formed upon the pin 16 adjacent the end plate 11, this lug being 70 preferably formed upon the side of the pin and adapted to prevent removal of the guard when the same is locked in position. When the guard is secured upon a door lock it is obvious that the lug 17 will prevent forcible removal of the guard, the extension lug 75 engaging the outer lock plate and preventing disengagement of the pin 16.

Positioned horizontally in the upper portion of the casing and secured to the partition plate 13 mounted therein, is a guide 80 pin 18, this pin being adapted to extend substantially across the inner portion of the casing and slidably support a lock bar 19.

The lock bar 19 comprises a substantially rectangular body 20 having formed through 85 the greater portion thereof a longitudinal slot 21, this slot being provided to enable the lock bar to slide upon the guide pin 18. One extremity of the guide bar is provided with a tapered extremity 22, the lower portion of this extension being somewhat narrower than the body 20 and adapted to slide upon a rivet 23. The other extremity of the lock bar is provided with a downwardly 90 extending plate 24, this plate being substantially the same width as the lock bar body and adapted to be actuated by the key extension. A coiled spring 25 is positioned about the guide pin 18 and is adapted to force the lock bar 19 toward one side of the 95 casing, that is, away from the partition plate 13.

The upper side of the casing 10 is provided with a pair of openings 26 formed near the extreme ends thereof and adapted 100 to receive therein the lower end of a hasp or yoke 27.

The hasp or yoke 27 is substantially U-shaped, the upper or neck portion 28 being 110 comparatively narrow and adapted to engage the shaft of a door knob, the intermediate portions diverging outwardly as

shown at 29 and carrying a comparatively short leg 30 and a longer leg 31. These legs are adapted to be inserted through the openings 26 formed in the upper portion of the 5 casing and lock the guard securely upon the door lock. The inner side of the short leg 30 is serrated at the lower portion thereof to form toothed members 32, these members being adapted to engage the tapered 10 extension of the lock bar and prevent removal of the hasp when the bar is in the extreme position. The long leg 31 of the hasp is provided with a cap 33 formed on the lower extremity thereof and adapted to prevent 15 removal of the hasp in the extreme upward position of the same, the cap extending about the lower portion of the leg and being of greater diameter than the opening 26 formed in the casing. When the hasp is 20 in the extreme upward position it is obvious that the hasp may be readily rotated but prevent disengagement with the casing.

The front portion of the casing 10 is closed by a removable end plate 34, this 25 plate being secured to the side of the casing by means of rivets 35 or in any suitable manner.

In use, the device may be readily employed upon the usual form of door locks, 30 being equally efficient when mounted upon the inner or outer side thereof. To secure the guard in position upon a door lock a suitable key is positioned upon the key pin 15 and inserted through the opening 36 35 formed in the removable end plate 34. When the key is rotated in a clockwise direction the extension thereon will engage the plate 24 formed on the lock bar, causing the said lock bar to slidably move in the direction of 40 the partition plate 13. When the lock bar is moved toward the partition side of the casing the extension 22 will be disengaged from the toothed members formed upon the hasp leg 30 thereby leaving the hasp to be readily 45 drawn upwardly and entirely free the short leg 30. The hasp or yoke 27 is then positioned over the door knob shaft and the projecting pin 16 inserted in the keyhole of the door lock. The short leg of the hasp is 50 then forced through the opening 26 and the hasp forced tightly into the guard casing, the lock bar being forced to engage the teeth formed on the leg 30 by means of the spring 55 25. When the hasp has been tightly forced into the casing it will be securely retained therein until released by the key member, the guard being thus securely positioned against the key hole. The projecting lug 60 17 formed upon the pin 16 will engage the inner side of the lock plate and prevent forcible removal of the guard.

It is to be understood that the form of my invention herewith shown and described is to be taken as the preferred example of the same, and that various changes as to the shape, size, and arrangement of parts may be resorted to without departing from the spirit of the invention, or the scope of the subjoined claims.

Having thus described my invention, I 70 claim:

1. A keyhole guard comprising a substantially rectangular body composed of end plates, and side walls, a partition plate mounted adjacent one of the said side walls, 75 a projecting pin formed on the outer side of one of the end plates, a key pin mounted on the inner side of the said plate and a guide pin horizontally mounted in the upper portion of the said casing; an L-shaped 80 locking bar having a longitudinal slot formed therein adapted to slide upon the said guide pin, and a tapered extension formed on one end of the said lock bar; and a hasp comprising a comparatively reduced 85 neck portion, the intermediate portion of the hasp diverging, extension legs formed on the lower portion of the said hasp, toothed members formed on one of the said legs, and a retaining cap formed upon the 90 other leg.

2. A keyhole guard comprising a body or casing having a pair of end plates, side walls, a vertical partition plate adjacent one of the said side walls, a projecting pin 95 formed on the outer side of one of the said plates, a key pin formed on the inner side of one of the end plates, a horizontal guide pin formed on the said partition plate, and means for securely fastening the said end 100 plates; a substantially U-shaped hasp comprising a substantially narrow neck member formed on the upper portion thereof, the intermediate portion thereof diverging and carrying on the lower extremities thereof a 105 pair of leg members, one of the said leg members being comparatively short and having toothed members formed on the inner side thereof, while the other leg member is provided with a cap; a lock bar having a 110 longitudinal slot formed therein, one extremity of the said lock bar being tapered to engage the teeth formed upon the short leg of the hasp, an extension plate formed on the outer extremity of the bar, and means 115 for supporting the bar, and a coiled spring member positioned about the guide pin for forcing the said locking bar toward the toothed leg of the hasp.

In testimony whereof, I have affixed my 120 signature.

FERNANDO C. BONIFACIO.
